METHOD OF MANUFACTURING VALVES

Sven J. Nordstrom, Piedmont, Calif., assignor to
 Merco Nordstrom Valve Company, Pittsburgh,
 Pa., a corporation of Delaware

Application May 12, 1936, Serial No. 79,399

7 Claims. (Cl. 29—157.1)

This invention relates to a novel method for the manufacture of irregular shaped containers or casings for high pressure service such as valves and the products formed thereby, and has particular application to the manufacture of plug valves.

In the manufacture of plug valves which will be discussed by way of example, particularly plug valves of the lubricated type, it is usual to completely assemble the valve with the plug carefully lapped into its seat and test it at double its rated maximum working pressure before the valve is shipped from the factory. As a result of such tests, it has been found, particularly with the types of valves designed for high pressure work, that after the test pressure was applied to the assembled valve, permanent changes in form of the valve body frequently resulted. Thus in a valve which was virtually finished and otherwise ready for sale, the accurate contact between the plug and body seating surfaces which had been so carefully produced would be destroyed and an examination would show that the plug would then be bearing heavily on the body over certain areas and would be out of contact with the body over other areas with resultant deleterious effects such as hard-turning, impairment of the seal, and non-uniformity of lubricant distribution in the case of lubricated valves. In such cases it has been necessary to regrind the plug into its seat and repeat the test.

According to the present invention this difficulty is obviated by subjecting a valve body preferably immediately prior to the final machining operations to an internal pressure substantially greater than the maximum rated working pressure of the valve to prestress the valve body, this prestressing treatment being carried out before the final machine cut of the valve seat is made. After the valve has been subjected to this prestressing treatment, the final machine cut of the valve seat is made, the valve plug is carefully lapped into the seat, and the valve is assembled and tested. When a valve, so processed, is put under pressure to test for leakage, it has been found that the test pressure does not cause any distortion of the valve seat, and it is not necessary to repeat any of the manufacturing steps.

The degree of pressure to be applied to prestress the valve body, and its duration, may be varied through a wide range. In general, the prestressing pressure applied to the valve should be substantially in excess of the test pressure or

any other pressure which the valve may be subjected to in service, and the duration of the treatment may vary from about two to five minutes or longer.

It is my theory in explanation of this invention, that due to the non-uniform thickness and irregular shape of the walls of such a container or casing as a valve body, when the valve herefore has been subjected to a test pressure, certain portions of the valve walls were stressed beyond their elastic limit thus causing the valve body to take a permanent set by cold flow. This did not materially weaken the valve because only sufficient distortion occurred to substantially equalize the internal stresses, or at least equalize them at the test pressure. Accordingly, in subjecting the valve bodies to a prestressing pressure higher than the test pressure, I believe I produce an equalization of the internal stresses up to the prestressing pressure applied so that no distortion or permanent set of the valve will thereafter occur when the valve body is subjected to a pressure up to the prestressing pressure.

In general, the prestressing pressure may be from about 16 $\frac{2}{3}$ per cent to 25 per cent in excess of the final test pressure which is to be applied to the valve, or about 133 per cent to 150 per cent in excess of the rated working pressure of the valve. The duration of the pressure treatment required may be determined by securing an extensometer gauge to the valve which registers elongations in units of one ten-thousandths of an inch, and observing the movement of the gauge, the treatment being completed when substantially no further movement of the gauge indicator is apparent. The valve body is then removed from the pressure treating machine and the tapered seat is machined to final dimension. It is preferred that the machining before treating allow approximately 0.010 inch to 0.015 inch to be removed after the prestressing operation. The valve plug is then inserted in the valve seat with a grinding compound and is carefully ground into the seat to an accurate fit. The valve is then finally assembled and tested.

The invention may be illustrated by several examples. A cast steel valve intended for a working pressure of 1200 pounds per square inch would be subjected to a test pressure of twice its working pressure or 2400 pounds per square inch after it is finally assembled. According to the present invention I subject the rough valve body to a prestressing pressure of 3000 pounds per square inch for a period of about three minutes, and thereafter complete the

machining and lapping of the valve body. In the case of a valve intended for a working pressure of 2000 pounds per square inch the test pressure would be 4000 pounds per square inch, 5 and a prestressing pressure of 5000 pounds per square inch could be employed for about four minutes. In the case of a valve intended for a working pressure of 3000 pounds per square inch the test pressure would be 6000 pounds per square 10 inch and a prestressing pressure of 7000 pounds per square inch for about five minutes would be employed.

It is therefore an object of the present invention to provide a novel method of manufacturing containers or vessels of irregular shape designed to resist relatively high pressures contained therein such, for instance, as valve bodies, such bodies after being treated according to my method being characterized by a permanent set 20 below a predetermined pressure and at the working pressure or pressures for which the container is designed.

A further object of my invention is a novel container or vessel to retain substances under 25 pressure, such for instance, as a valve body, wherein the body is set permanently as regards the intended working and testing pressures and no cold flow occurs under such pressures to deform the body.

30 Still a further object of my invention is the provision of novel apparatus for prestressing a valve body or like container designed to contain substances under pressure wherein the degree of prestressing may be accurately controlled.

35 Other objects and advantages of my invention will be apparent from the following description and reference to the accompanying drawing wherein:

Figure 1 is a side elevation of a preferred 40 apparatus for carrying out my new method.

Figure 2 is a vertical section of a valve body to be treated.

Referring to the accompanying drawing, a preferred embodiment of my treating apparatus 45 comprises a heavy bench 1 having a stationary head 2 securely bolted thereto, and a movable head 3. The head 2 has a plurality of undercut radial slots 4 which receive the heads of suitable bolts by which the hollow extension 5 is secured 50 thereto. The slideable head 3 has a face plate 6 with similar undercut slots whereby the extension 7 is secured thereto. The extension 7 has a plate 8 for closing the end of the valve 10 to be treated, and the opposite end of the valve 55 abuts the face of hollow extension 5, suitable gaskets being interposed to prevent leakage. The movable head 3 is guided on blocks 11 slideable on the edge 12 of the bench. A cross head 13 is similarly slideable on the edge or tracks 12 60 and is connected to the head 3 by a screw 14 and rotatable collar 15 having a handle 15' extending therefrom by means of which the distance between cross head 13 and head 3 may be accurately adjusted. Two links 16 and 17 are 65 swiveled to the cross head 13 and fixed head 18 and are pivotally connected by a pivot pin 19. A hydraulic cylinder 21 is pivotally secured to extensions 22 depending from the bench on both sides, and a piston rod 23 is secured to the pivot 70 19 at one end and to a piston (not shown) in the cylinder 21 at its other end. Inlet pipe 24 and outlet pipe 25 lead from a four way valve 26, connected to a supply pipe 27 which conducts kerosene, water, or other fluid under pressure 75 for operating the hydraulic piston and connect-

ed to a suitable outlet. The valve is subjected to internal pressure by liquid introduced through pipe 29 to the hollow extension 5, suitable valves (not shown) being provided to control the admission of the liquid.

5 The valve casing 10 has a transverse passageway 31 therethrough for flow of fluid and a tapered seat 32 which is shown in exaggerated outline as having a rough machined surface. An extension of the casing has a threaded bore 33 1 therein which is closed during the treatment by any suitable means such as a bolt 34 held in sealing relation by a washer 35 and nut 36 threaded on its outer end. A removable master cover plate 37 is bolted to the casing, and has 15 the handles 38 welded thereon to facilitate handling of the valve as by a crane. The valve is readily adjusted with reference to the extensions 5 and 7 by a jack 39, which it will be observed is used merely as a support.

20 A preferred method of practicing my invention is as follows:

The bolt 34 is inserted through the larger end of the seat into the bore 33 and is secured in place by nut 36 and washer 35. The valve cover 25 37 is bolted to the valve body and the valve lowered as by a crane onto the jack 39, the U-shaped handles 38 serving as a convenient engaging means. The jack 39 is then adjusted to raise the valve and bring the inlet and outlet 30 connections of the valve body in line with the extensions 5 and 7 of the fixed and movable heads respectively. A gasket is inserted between the valve and the face of extension 5 and the nut 15 is rotated by means of bar 15' to bring 35 the movable extension 7 into proper position with the other end of the valve passageway. A gasket is then inserted between the face of the extension 7 and the valve and fluid is turned into the hydraulic cylinder 21 to draw the piston 40 rod 23 downwardly and expand the toggle link connection 17 and 16 thereby securing the valve between the fixed and movable heads 2 and 3 respectively. It will be noted that the valve body, so disposed, is substantially unconfined 45 and capable of almost unrestricted deformation. Liquid under pressure is then admitted through the pipe 29 and the pressure is maintained for a period of several minutes. Under this pressure stresses are set up in the valve walls which cause 50 the valve body, or at least portions thereof, to take a permanent deformation. The pressure is maintained until no further deformation occurs and is then relieved, the valve removed from the apparatus, and the seat 27 is smoothly machined 55 to the required dimensions. A plug machined to the proper size is then inserted in the valve seat 27 and if desired, is lapped into position to produce an accurate fit. The valve is then assembled and is ready for final test.

60 It will be understood that the method of the present invention may be carried out in other apparatus embodying my invention, and that I do not intend to be limited to treatment of the particular type of irregular body illustrated.

65 The invention may be embodied in other specific forms without departing from the spirit or essential characteristics thereof. The present embodiment is therefore to be considered in all respects as illustrative and not restrictive, the 70 scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In the manufacture of plug valves, the method which comprises subjecting a substantially unconfined plug valve casing having its seat in a roughly finished state to an internal pressure substantially in excess of its rated working pressure and sufficient to cause permanent deformation of portions only thereof and maintaining said pressure until substantial permanent deformation of the casing has occurred, and thereafter machining the seat to its final dimension. 5
2. In the manufacture of plug valves having cast steel bodies, the method which comprises subjecting a substantially unconfined valve body with its seating surface unfinished to an internal pressure substantially in excess of its rated working pressure and sufficient to cause permanent deformation of portions only thereof and maintaining said pressure until substantial deformation of the casing has occurred, and thereafter machining and lapping the valve seat to its final dimension. 10
3. In the manufacture of irregular casings, such as valve casings designed to retain substances under pressure, having internal machined surfaces and which are to be subjected to test pressures in excess of rated working pressures, the method which comprises subjecting a substantially unconfined incompletely machined casing to internal pressure substantially in excess of the test pressure to be used, said internal pressure being sufficient to cause permanent localized distortion in portions of the casing, maintaining said internal pressure until substantially no further distortion occurs, removing said internal pressure, and machining the internal surface to final size. 15
4. In the manufacture of irregular casings, such as valve casings designed to retain substances under pressure and having internal machined surfaces, the method which comprises subjecting a substantially unconfined incompletely machined casing to internal pressure substantially in excess of the pressure to which the casing is to be subjected after it is completely machined, said internal pressure being sufficient 20
- to cause permanent localized distortion in portions of said casing, maintaining said internal pressure until substantially no further distortion occurs, removing said internal pressure, and machining the internal surfaces to final size. 25
5. In the manufacture of valves of the type subjected to high pressures during normal operation and having accurately machined surfaces, the method which comprises subjecting a substantially unconfined incompletely machined valve casing to internal pressure substantially in excess of any pressure to which the valve may be subjected during test or normal operation after the casing has been completely machined, said internal pressure being sufficient to cause permanent localized distortion in portions of said casing, maintaining said internal pressure until substantially no further distortion occurs, removing said internal pressure and machining said surfaces to final size. 30
6. In the manufacture of valves having machined seating surfaces, the method which comprises subjecting a substantially unconfined incompletely machined valve body to an internal pressure of about 133 per cent to 150 per cent in excess of its rated working pressure while simultaneously gauging the deformation of the casing caused by said pressure, maintaining said pressure until substantially permanent localized deformation occurs, removing said pressure, and thereafter finishing the seating surfaces to final dimensions. 35
7. In the manufacture of valves having machined seating surfaces and which are to be subjected to test pressures in excess of rated working pressures, the method which comprises subjecting a substantially unconfined valve body to internal prestressing pressure about 16½ per cent to 25 per cent in excess of the final test pressure to which the valve is to be subjected, said prestressing pressure causing permanent localized distortion in portions of said body, maintaining said prestressing pressure until substantially no further distortion occurs, removing said prestressing pressure and machining the seating surfaces to final size. 40
